DESIGN FOR A DENTAL PLATE BRUSH OR SIMILAR ARTICLE

Lou Dunlap Laird, Columbus, Ohio

Application November 29, 1937, Serial No. 73,239

Term of patent 7 years

To all whom it may concern:

Be it known that I, Lou Dunlap Laird, a citizen of the United States, residing at Columbus, in the county of Franklin and State of Ohio, have invented a new, original, and ornamental Design for a Dental Plate Brush or Similiar Article, of which the following is a specification, reference being had to the accompanying drawing, forming a part thereof.

Fig. 1 is a perspective view of a dental plate brush or similar article showing my new design;

Fig. 2 is a top plan view thereof on a slightly enlarged scale;

Fig. 3 is a side elevational view thereof on a slightly enlarged scale.

I claim:

The ornamental design for a dental plate brush or similar article, as shown.

LOU DUNLAP LAIRD.
